Primary Examiner — Calvin E Vansant*Assistant Examiner* — Eidiol Ghigliotti Torres(74) *Attorney, Agent, or Firm* — Saidman Design Law Group**CLAIM**

The ornamental design for a cab for construction vehicle, as shown and described.

DESCRIPTION

FIG. 1 is a perspective view of a cab for construction vehicle showing our new design;

FIG. 2 is another perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the cab for construction vehicle which form no part of the claimed design.

The oblique shade lines in the figures show transparency or translucency.

1 Claim, 8 Drawing Sheets(56)
